UNITED STATES PATENT OFFICE

CARL W. LOHSTROH, OF CINCINNATI, OHIO.

HOLDER.

1,277,230.

Specification of Letters Patent. Patented Aug. 27, 1918.

Application filed November 24, 1917. Serial No. 203,777.

To all whom it may concern:

Be it known that I, CARL W. LOHSTROH, a subject of the Emperor of Germany, and a resident of Cincinnati, in the county of 5 Hamilton and State of Ohio, have invented certain new and useful Improvements in Holders, of which the following is a specification.

My invention relates to adjustable and interchangeable utensils, and its object is to 10 economically produce a readily adjustable but tightly clamping holder for scrubbing-brushes and the like, or other utensils having solid backs or handles, and which it may 15 be desired to fasten at the end of a long handle for use on the floor, walls or ceiling or in cleaning windows or other like operations.

My invention consists in the improved 20 article of manufacture and in the details of its construction and in the combination and arrangement of such details as will herein-after be more fully described and claimed.

In the drawing:

25 Figure 1 is a perspective view of a holder embodying my invention;

Fig. 2 is a vertical cross-section on a plane corresponding to the line 2—2 of Fig. 1; and

30 Fig. 3 is a detail perspective view of the blank from which the main part of my improved holder is formed.

As I prefer to construct this holder, a single rectangular piece of sheet metal 1 (Fig. 3) has pairs of slits 2 cut in from its 35 rear edge 3 substantially at right angles to said edge and short distances from respective ends 4 of the plate. These slits 2 are of length about equal to the distance between the two slits of the pair.

40 Through substantially the central parts of the areas of metal remaining between the two slits of the pairs, are punched holes 5.

Near the front edge 6 of the plate 1, and in alinement with the holes 5 on lines at 45 right angles to the edges 3 and 6, are punched holes 7; and just inward from these holes are punched long narrow rectangular slots 8.

Also, preferably, midway of the length of the main part of the plate that lies between the inner ends of the slits 2 and the 50 slots 8 is punched a large oval opening 9 preferably somewhat nearer the back edge 3 than it is to the front edge 6.

The plate 1 thus being cut, it has a front 55 flange 10 formed up along the dotted line A (Fig. 3) approximately coincident with

the inner edges of the slots 8, this flange 10 being formed to stand up substantially perpendicular to the main part of the plate, as seen in Figs. 1 and 2. At the back, the parts 60 of the plate between the slots 2 are formed up while the alternate remaining parts at the ends and in the middle are formed down; all of these parts being formed substantially perpendicular to the main part of 65 the plate. The formed-up parts constitute ears 11, while the formed-down parts constitute the middle clamping flange 12 and the clamping ears 13 near the ends.

With the plate thus formed, the holes 5 70 and 7 near respective ends are in substantial alinement, and the slots 8 lie horizontally under the holes 7 immediately adjacent to the main part of the plate.

To complete this detail of the utensil, the 75 tube 14 has its lower end suitably beveled and fitted into the elliptical opening 9 in the plate, around which the tube is soldered or otherwise suitably fixed to the plate; it being understood that the elliptical opening 9 80 is of proper formation to admit the elliptical beveled lower end of the tube 14 snugly.

The movable clamping members 15 are simply flat metal bars somewhat thicker than the plate 1, each having one end part 85 16 bent up and provided with a threaded opening 17 and having the other end part 18 bent down; these parts 16 and 18 lying substantially perpendicular to the main part, which main part is of such length that 90 when the member 15 is projected through the corresponding slot 8 in the plate 1 with the end part 18 projecting down outside the flange 10, the upwardly extending part 16 at the other end comes close to the inner 95 side of the corresponding ear 11.

Screws 19 of the right diameter to fit snugly but turn freely in the alined openings 5 and 7 have threads throughout their lengths between the corresponding tongue 11 100 and the flange 10 when inserted through these openings 5 and 7, and are screwed through the corresponding upright end parts 16 of the clamping members 15. At its rear end each screw has a suitable head 20 105 for conveniently turning it; and outside the rear of the corresponding tongue 11 and outside the front of the flange 10, each screw has radially through it pins 21 and 22, respectively, which limit the end-play of 110 the screws 19. Thus, as each screw 19 is turned in one direction or the other, it

causes the clamping member 15, with which it is associated as above described, to travel forwardly or rearwardly across the plate 1 bringing its downwardly extending forward 5 end part 18 closer to or farther from the downwardly extended flange 12 and tongues 13 on the rear of the plate.

Thus, the holder is provided with adjustable clamping means near each end which 10 is adapted to grasp objects, as for instance, the back 23 of the brush 24 in Fig. 2, of varying widths and of any practical length, since the ends of the holder are entirely open. The tube 14 forming a ferrule that 15 will fit on a suitable handle of any desired length, it will be seen that the holder affords a means of mounting such utensils as the brush 24 on a suitable handle as the handle 25 in Fig. 2, for whatever use is desired of 20 the utensil thus mounted. At the same time, the device is very simple, economical to produce, and efficient and reliable in operation.

Having fully described my invention, 25 what I claim as new and desire to secure by Letters Patent is:

1. A holder having open ends and comprising an upstanding flange at one side, an upstanding tongue at the opposite side, a screw extending across said holder and journaled and held against end-play in said flange and tongue, a movable clamping member lying across said holder under said screw with an upwardly extending part through 30 which said screw is threaded, and a downwardly extending part outside said flange, downwardly extending means on the side of 35 said holder adjacent to said tongue to co-

operate with the downwardly extending part of said movable clamping member, and means for mounting said holder on a suitable handle. 40

2. A holder comprising a main middle flat part with upstanding parts at opposite sides, and a downwardly extending part at one of said sides; a screw lying across said main flat part and journaled in and held against end-play in said upstanding parts, a movable clamping member lying across said main flat part with an upwardly projecting part through which said screw is threaded, and extending through the upstanding part at the edge opposite said downwardly extending parts, and extending downwardly past said opposite edge to coöperate with said downwardly extending part, and means to 50 mount said holder on a suitable handle. 55

3. As a new and improved article of manufacture, a body for a holder composed of a single rectangular plate with a flange bent up along one side, and having upper and lower openings through said flange near respective ends of the plate, and said plate having pairs of slits cut into it from its opposite edge near respective ends of the plate, and having openings through the parts of the plate between the slits, these parts being bent up, and the alternate remaining parts of the plate being bent down, substantially as and for the purposes specified. 60 65

CARL W. LOHSTROH.
